Specification for Design.

Patented Mar. 8, 1910.

Application filed November 6, 1909. Serial No. 526,674. Term of patent 7 years.

To all whom it may concern:

Be it known that I, WILLIAM C. HENDERSON, a citizen of the United States, residing at Baltimore, in the State of Maryland, have invented a new, original, and ornamental Design for Label-Blanks, of which the following is a specification, reference being had to the accompanying drawings, forming a part thereof.

The drawing illustrates the design of the

label blank, the figure of the drawing being an elevation showing the design thereof.

I claim:

The ornamental design for a label blank, as shown.

WILLIAM C. HENDERSON.
